UNITED STATES PATENT OFFICE.

THOMAS MCL. DAVIS, OF WASHINGTON, DISTRICT OF COLUMBIA, ASSIGNOR TO WIRED RADIO, INC., OF NEW YORK, N. Y., A CORPORATION OF DELAWARE.

SELECTIVE SIGNALING SYSTEM.

Application filed May 12, 1926. Serial No. 108,666.

My invention relates broadly to alternating current circuits and more particularly to an electrical tuning system for radio frequencies whereby by accurate adjustment of the tuning circuits it is possible to accept a desired frequency, to the exclusion of undesired frequencies.

One of the objects of my invention is to provide a radio frequency trap circuit for signal receiving systems for excluding interfering frequencies from the signal receiving circuit while being efficiently responsive to a selected frequency.

Another object of my invention is to provide an arrangement of frequency selective circuits which may be readily adapted for connection in a variety of alternating current systems for obtaining a high degree of selectivity.

Another object of my invention is to provide a double trap circuit for signal receiving systems having a plurality of branches which may be selectively connected in the receiving circuit for securing efficient response to signals of a given frequency while excluding from the receiving circuit signals of interfering frequencies.

Another object of my invention is to provide a double trap circuit for signal receiving systems in which a plurality of branches are provided for establishing two series circuits through the two traps to the signal receiving system where one of the traps may be tuned to resonance with the interfering signal for the exclusion thereof while the second trap may be adjusted so that its capacitive reactance will be equal and opposite to the inductive reactance of first or excluding unit for securing selective reception of incoming signaling energy.

Still another object of my invention is to provide a combination of trap circuits for signal receiving systems wherein a pair of independent series paths for the incoming signals may be provided through inductive or capacity elements which are disposed in parallel relationship, with means for independently shunting the parallel connected elements for adjusting one trap unit for the exclusion of the undesired frequency.

A still further object of my invention is to provide an interference prevention unit for signal receiving circuits wherein two independent traps are employed with means for

separately tuning each of the trap units for establishing two series resonant circuits through the traps, each of the traps being parallel connected devices which may be adjusted for the exclusion of undesired frequencies, while permitting selective reception of a desired frequency.

A parallel tuned circuit when placed in a radio circuit such as an antenna, will act as a trap to the frequency to which it is tuned by virtue of its high series impedance. The effect of such a unit is not confined to the resonant frequency but is more or less effective over a band, the width of which depends upon the inherent losses of such a combination while the degree of maximum exclusion also depends upon the same losses.

In view of the fact that this objectionable breadth does exist, even in the lowest loss trap units practicable to build, I have devised various forms of double trap units which to a great degree reduce this effective breadth, making it possible to receive signals very close to the trapped frequency and much closer than it has heretofore been possible.

My invention will be more clearly understood by referring to the accompanying drawings in which:

Figure 1 illustrates one arrangement of the double trap circuit of my invention connected in a radio receiving system; Fig. 2 illustrates a modified arrangement of the double trap circuit for signal receiving circuits; Fig. 3 shows still another modification of the double trap circuit of my invention; and Fig. 4 illustrates the application of the double trap circuit of my invention to wired radio receiving systems.

I have illustrated the traps schematically in the drawings as applied to an aperiodic antenna circuit and to a wired radio system which feeds a receiver thru an inductive coupling. In Fig. 1 of the drawings two traps 9 and 10 are shown in an antenna ground circuit 1-2. The signal receiving circuit is represented as coupled to the antenna ground system 1-2 through coupling transformer 3 having primary winding 4 and secondary winding 5 tuned by means of variable condenser 6. The tuned input circuit 5-6 connects to an electron tube amplification system which I have represented by electron tube 7, the output circuit of

which extends through coupling transformer 8 to the remainder of the receiving apparatus.

Each trap 9 and 10 employs a variable condenser 11 and 14 with fixed or step-variable inductance systems 12 and 15. With this arrangement it is possible to tune one trap to exclude an interfering signal while the other trap is shorted out by virtue of switches 16 or 17, then by cutting in the second trap by means of switches 16 and 17 it may be tuned to improve the intensity of the signal which is desired for reception. This improvement is most effective when the two signals are comparatively close together and it is in this range that the double trap unit is most valuable. By reference to Fig. 1, it will be noted that when both traps 9 and 10 are in the circuit, there are two parallel traps in series with the antenna 1 and there are two series circuits thru the two traps from the antenna 1 to the receiver. Either of the parallel circuits may be tuned to resonance with the interfering signal for exclusion while the second trap condenser 14 can be tuned so that its capacitive reactance will be equal and opposite to the inductive reactance of the first or excluding unit. If the two traps have similar inductances and the interfering and desired signal frequencies are close, both of the series paths 11, 15, and 12, 14 will be close to resonance affording one series path of zero and another of nearly zero reactance to the desired signal while the parallel trap in one case excludes the interference and the other parallel trap is also effective on whatever frequency it may be resonant. This combination is practically independent of effect from antenna capacity variation. The double trap unit has the added advantage of giving double exclusion to a strong interference by tuning them both to resonance.

In Fig. 2 a combination of two traps 9 and 10 which possess all of the features hereinbefore mentioned are provided, but in addition, have a variometer 18 in one unit instead of a fixed inductance thereby making it possible to obtain two series resonant circuits thru the traps when trap 10 is set for exclusion.

In Fig. 3 two traps 9 and 10 are shown in which both inductances 18 and 19 are variable which gives additional flexibility, permitting the use of either unit as the exclusion trap with the ability to obtain series resonance thru either or both of the legs by tuning the other trap inductance and capacity elements separately to series signal resonance.

In Fig. 4 I have shown the double trap system 9—10 of my invention applied to a wired radio receiving circuit where a desired carrier frequency may be received to the exclusion of other carrier frequencies.

The combination of the two parallel tuned traps, which have means for independently rendering the tuning elements thereof effective or ineffective, operates to exclude undesired frequencies from the signal receiving circuit while permitting selective reception of a desired frequency.

While I have shown several different embodiments of the double trap circuit, I desire that it be understood that even further modifications may be made and that no limitations upon my invention are intended other than are imposed by the scope of the appended claims. For example, I may readily employ the principles of my invention in the elimination of harmonic frequencies in transmitted circuits. A variety of applications of my invention will readily suggest themselves to those skilled in the art.

What I claim as new and desire to secure by Letters Patent of the United States is as follows:

1. An interference prevention circuit for signal receiving systems comprising in combination with a signal receiving circuit a pair of trap circuits, each of said trap circuits comprising variable inductance and capacity connected in parallel, with one of said trap circuits series connected with the other of said trap circuits and means for independently shunting either of said trap circuits, the inductance and capacity in one of said trap circuits being arranged to be tuned to resonance with an interfering frequency for the exclusion thereof, while the other of said trap circuits may have its capacitive reactance adjusted to a value equal and opposite to the inductive reactance of the other trap circuit.

2. An interference prevention circuit for signal receiving systems comprising in combination with a signal receiving circuit, a pair of series connected trap circuits each consisting of tunable elements connected in parallel, a tunable element of one of said trap circuits providing with a tunable element of the other of said trap circuits a series path to said signal receiving circuit, whereby two series circuits are provided through said trap circuits to said signal receiving circuit, and means for rendering the elements in a selected one of said trap circuits effective or ineffective for the selective reception of a predetermined frequency to the exclusion of other frequencies.

3. A signal receiving system comprising in combination with a signal receiving circuit, a pair of trap circuits each having parallel connected tunable elements, with the tunable elements of one trap series connected with the tunable elements of the other trap and disposed in series with said signal receiving circuit, separate tunable elements in each of said trap circuits affording a series

- path of substantially zero reactance and other tunable elements in each of said trap circuits, affording an independent series path 5 approaching substantially zero reactance to the desired signal frequency whereby one of the traps excludes undesired frequencies and the other of said traps operates to further exclude undesired frequencies for the selective reception of a desired frequency.
- 10 4. In a signal receiving system an interference prevention circuit connected in series with the receiving system, said interference prevention circuit comprising separate paral-

lel connected systems, each including capacitive and inductive reactances, one of said 15 parallel connected systems being arranged to be tuned to resonance with the interfering frequency for the exclusion thereof from said signal receiving circuits, while the other said parallel connected system has its capacitive reactance adjustable to a value equal and opposite to the inductive reactance of the first mentioned parallel connected system for excluding undesired frequencies and selectively receiving desired frequencies.

THOMAS McL. DAVIS.
